UNITED STATES PATENT OFFICE.

LOUIS N. D. WILLIAMS, OF OGONTZ, PENNSYLVANIA.

KNITTING-MACHINE NEEDLE.

1,120,989.

Specification of Letters Patent. Patented Dec. 15, 1914.

Application filed June 19, 1913. Serial No. 774,594.

To all whom it may concern:

Be it known that I, Louis N. D. Williams, a citizen of the United States, residing in Ogontz, Pennsylvania, have invented 5 certain Improvements in Knitting-Machine Needles, of which the following is a specification.

The object of my invention is to provide means for cutting the stitch upon a knitting machine latch needle so as to release the needle from the stitch without casting the latter over the hooked end of the needle and therefore without closing the latch, the latter being left open so that the new yarn can be 15 readily applied to the hook of the needle at a succeeding yarn feed, thus overcoming the necessity of employing special means for insuring the opening of the latches at a point between the stitch casting and yarn feeding 20 points as in ordinary machines of the latch needle type.

In the accompanying drawing Figures 1 and 2 are side elevations, on an enlarged scale, of a knitting machine latch needle 25 constructed in accordance with my invention, Fig. 1 showing the needle in knitting position and Fig. 2 in position to cut the stitch; Figs. 3 to 9, inclusive, are side elevations showing other combinations of needle 30 and knife or knives in accordance with my invention, and Fig. 10 is a horizontal section, on an enlarged scale, on the line *a—a*, Fig. 1.

In the drawing, 1 represents the stem of 35 the needle, 2 the hooked upper end of the same, and 3 the swinging latch, all of which are similar to those of latch needles as now constructed. Combined with the stem of the needle, however, is a knife, that shown in 40 connection with the needle of Figs. 1 and 2 being indicated at 4, and being, as there shown, triangular in shape and sharpened on its upper inclined face. This knife is so located on the stem of the needle that during 45 the ordinary reciprocations of the needle required by the knitting operation it will not approach the top of the needle carrier and hence will have no action upon the stitch lying upon the needle, this condition being 50 that represented in Fig. 1. When, however, the knitting of the web has been completed and it is desired to free it from the needles a high lift is imparted to each needle so that 55 its knife will act upon and sever the stitch last formed on the needle, as shown in Fig.

2, thereby releasing the knitted web from the needles.

When, in the operation of an ordinary latch needle knitting machine, the stitch clears the latch on the rise of the needle the 60 closing of said latch is prevented by the usual latch guard of the machine but in casting off the stitches over the hooked ends of the needles, in the ordinary way, the latch is closed against the hook by the escaping 65 stitch and is likely to remain in a closed or partly closed position, and must be opened before the new yarn can be laid in the hook, hence a necessary part of the equipment of an ordinary latch needle knitting machine 70 is a device for thus opening the latches after the casting off of the stitches from the needles. When, however, the fabric is cast off in accordance with my invention, by severing the stitches, the latches remain in 75 their open position and special latch openers are rendered unnecessary. During the cutting operation the stitches on the needles are preferably held by engagement with the usual web holder 5 as shown in Fig. 2. Instead of being designed to cut the stitch 80 upon an up stroke of the needle the knife may be designed to cut upon a down stroke of the same, as shown for instance at 4^a in Fig. 3.

In connection with the stitch-severing knife I find it advisable to use a hook which has a tendency to engage the cut stitches and pull them free from the adjacent stitches of the web and thus leave a course of clean 85 stitches at the edge of the web. The preferable method of accomplishing this result is to use a hooked knife, as shown for instance at 4^b in Fig. 4 or at 4^c in Fig. 5, 90 although if desired the hook may be independent of the knife, as shown for instance at 6 in Fig. 6, or at 7 in Fig. 7, the hook in the latter case being on the back of the needle stem, and acting upon the cut stitch through the medium of a preceding stitch, 95 or by sharpening the lower edge of the hook 100 the latter may be caused to cut said preceding stitch. The knives and hooks may, if desired, be formed integral with the stem of the needle but the preferable plan is to 105 provide each knife or hook with a shank 8 fitting within a slot cut in the stem of the needle and secured therein by soldering, brazing, riveting, or other available means. 110 While it is preferable to secure the cutting

knife directly to the shank of the needle, this is not essential to the broader embodiment of my invention, as the knife may, if desired, be formed upon a stem independent 5 of the needle stem such for instance as represented at 9 in Fig. 7, this stem having a butt which is controlled by a cam independent of that which controls the needle, whereby by the knife-carrying stem may be actuated 10 at those stages in the operation of the machine where it becomes necessary to free the needles from the stitches last formed upon them, or such independent knife may co-operate with a knife secured to the needle 15 stem, as shown for instance in Fig. 8, so as to act like a pair of shears.

The independent knife may, if desired, be located at the back of the needle stem so as to cut the stitch preceding that upon the 20 needle, as shown for instance at 9a in Fig. 9, the knife 10 operating through a slot 11 in the top of the needle cylinder and the knife stem presenting a shoulder 12 for engagement with the inclined base 13 of said slot 25 so that when the stem-9a is raised its upper or knife-carrying end will be thrown outward carrying the needle with it and thus serving to tighten the stitch which is to be severed.

30 I am aware that it has heretofore been proposed to provide a loop-retaining hook with a knife which would sever the loop as the stem of the hook was raised through the same and also that it has been proposed to 35 provide a needle with a latch sharpened on the outer side so as to sever the loop as it slipped over the latch, but, in the latter case, the closing of the latch was necessary in order to effect the severing of the loop, whereas 40 my invention has for its purpose the severing of the loop without closing the latch. In all cases, therefore, the knife which I employ in connection with the needle is situated below the pivot point of the latch.

I claim:

45 1. A knitting machine latch needle having combined therewith a knife for severing a stitch previously formed upon the needle, said knife operating below the pivot of the latch.

50 2. A knitting machine latch needle whose stem is provided with a knife for severing a stitch previously formed upon the needle, said knife being located below the pivot of the latch.

55 3. A knitting machine latch needle having a knife for severing a stitch previously formed upon the needle, said knife being separate from but secured to the stem of the needle at a point below the pivot of the latch.

60 4. A knitting machine latch needle combined with a knife for cutting a stitch previously formed upon the needle, and a hook for clearing said severed stitch from the web.

65 5. A knitting machine latch needle having a knife carried by the stem of the needle and serving to sever a stitch previously formed upon the needle, and a hook for clearing said severed stitch from the web.

70 6. A knitting machine latch needle having combined therewith a hooked knife, for first severing a stitch previously formed upon the needle and then clearing said severed stitch from the web.

75 7. A knitting machine latch needle having a hooked knife carried by the stem of the needle and serving to sever a stitch previously formed on the needle, and then to clear said severed stitch from the web.

In testimony whereof I have signed my name to this specification, in the presence of two subscribing witnesses.

LOUIS N. D. WILLIAMS.
